UNITED STATES PATENT OFFICE

PAUL R. EGGER, OF DAVENPORT, IOWA

TELEVISION APPARATUS

Application filed March 22, 1930. Serial No. 438,004.

My invention relates to improvements in television apparatus.

The objects of my invention are:

1. To provide improved means in transmitting sets for scanning the object to be transmitted televisionally and to provide improved means in receiving sets for receiving and transmitting to the screen the beams of light from the glow-lamp;
  2. To provide means in transmitting sets by which the object to be transmitted may be scanned in continuous bands instead of by separate and distinct dots of light and to provide means in receiving sets by which the light received may be cast upon the screen in a series of successive bands rather than in a series of separate and distinct points of light;
  3. To provide means by which the apparent black lines between the apparent lines of illumination on a screen of a receiving set, may be reduced or eliminated and also to provide means by which the apparent white lines between the illuminated lines on such a screen due to overlapping of paths of light or illuminated bands, may be reduced or eliminated;
  4. To provide a simplified, improved multiple mirror for television sets;
  5. To provide means by which objects may be transmitted televisionally either by direct light reflected from the object or by casting an image of the object upon a screen and transmitting such image;
  6. To provide improved means for synchronizing television apparatus.
- I attain these objects by the means illustrated in the accompanying drawings, in which,—
- Figure 1 is a plan view of a television camera embodying my invention, but with the top or cover plate removed;
- Figure 2 is a side elevation of the same with the side plate of the housing removed to expose the interior;
- Figure 3 is a rear elevation of my apparatus with the rear housing plate removed to disclose the interior;
- Figure 4 is a greatly enlarged detail of my multiple mirror;

Figure 5 is an enlarged cross-sectional detail on the line 5—5 of Figure 4;

Figure 6 is a view of the slotted slide which is removably mounted upon one of the lenses;

Figure 7 is a diagrammatic view of a receiving set;

Figure 8 is a diagrammatic view of a transmitting set but with the space between the object, 15, and the screen, 6, foreshortened. In transmitting, my reflector may be used in the combination shown in Figure 8 or if desired, the screen, 6, and the lenses, 4 and 5, may be omitted, the object may be properly illuminated and the light may be reflected directly from the object to the mirrors, 3'. When so used, it will be advisable to enlarge the reflecting element, 3, to a considerable extent.

Similar numerals refer to similar parts throughout the several views.

I have not attempted to show the apparatus for transmitting the light waves after they have been thrown upon the photo-electric cell of the transmitter nor the apparatus for receiving the electric waves from the air, wire or other medium by which they are transmitted and bringing them to the neon or glow-lamps before being amplified to be cast upon the screen. Such apparatus is well known and in common use and my special devices may be applied to and used with any desired form thereof.

My apparatus comprises a box-like housing, 11, of wood or any other suitable material. For convenience I refer to the right end of Figure 1 as the front and to the left end of it, as the rear; also to the top of Figure 1, as the left side of the camera or housing and the bottom of Figure 1 as the right side of the camera or housing.

The housing, 11, has a horizontal partition, 12, secured transversely thereto and extending from the front nearly to the rear of the housing. A vertical, light-proof partition, 13, is mounted in the camera and extends from the front, back nearly to the rear of the partition, 12, where it is joined by transverse partitions, 14 and 14'. A screen, 6, is mounted between the partition, 13, and the

right side wall of the camera. In the front plate of the housing I mount a lens, 7, adapted to focus upon the screen, 6, and image of objects coming within the field of the lens, 7.

5 In the partition, 14', I mount a plano-concave lens, 5, adapted to transmit the light rays from the screen, 6, in parallel lines to the plano-convex lens, 4, which in turn transmits them to the revolving reflecting element, 3. 10 This reflecting element, 3, comprises a shaft of Monel metal or other metal adapted to take 15 a mirror-like finish and has a plurality of mirrors, 3', cut transversely of the shaft through the center line thereof. Each mirror 20 comprises a flat surface as long as the diameter of the shaft and the body of the shaft is cut away very much like a twist drill. The successive mirrors are cut with an axial angular variation sufficient to permit the 25 beam of light transmitted by one mirror to clear the photo-electric cell before the beam of light from the next succeeding mirror strikes the photo-electric cell. I prefer an angular variation of approximately two and a half degrees. The face of each mirror, 3', is plane.

The reflecting element, 3, has its upper end mounted in any suitable form of bearing, 16, united to the top of the housing, 11, and its 30 lower end is preferably united by a chuck, 17, to the shaft of a motor, 18, mounted within the housing or box, 11.

Upon the bottom of the box, 11, I mount a bearing plate, 25, carrying a plurality of 35 heavily grooved rollers, 23, by studs, 24, or other suitable means. The motor, 18, is mounted within a cylindrical sleeve, 20, and the lower end of the sleeve, 20, is provided with an inwardly extending flange or track, 40 21a, which extends into the grooves of the rollers, 23, and supports thereon the sleeve, 20, and the motor, 18, which is adjustably secured within the sleeve by the set screws, 19.

Around the base of the sleeve, 20, I provide 45 a spur gear, 21, which meshes with a drive gear, 22, mounted upon the shaft, 26. The shaft, 26, has its lower end rotatably mounted in a bearing block, 27, secured to the bottom of the camera and its upper end extends 50 through the top of the camera and is provided with a knob, 28, by which it may be turned. It will be seen that the turning of the knob, 28, will turn the sleeve, 20, which will carry with it the motor, 18, and in this 55 way the reflecting element, 3, may be advanced or retarded.

When used as a transmitting set, the mirrors, 3', will reflect successive bands of the image appearing upon the screen, 6, and 60 transmit them through the lens, 2, to the photo-electric or light-sensitive cell, 1; and as the light transmitted by the mirrors, 3', varies in intensity, the light reflected to the cell, 1, will vary and the electric current set 65 up within the cell will also vary. The vary-

ing current is then led from the cell, 1, by suitable wiring, to the amplifying and transmitting apparatus.

When used as a receiving apparatus, a neon or glow-lamp, 1a, is substituted for the cell, 1. The receiving current after being 70 amplified and led to the glow-lamp, 1a, develops a varying light therefrom and the beams of light from the lamp, 1a, are transmitted through the lens, 2, to the reflecting element, 3, and thence reflected by the mirrors, 3', through the lenses, 4 and 5, to the screen, 6, where they become visible to the eye.

The screen, 8, with the slot, 8a, therein, is removed from the lens, 2, when the apparatus 80 is used for receiving and the lens, 2, focuses the light from the glow-lamp, 1a, in a vertical line upon the reflecting element, 3.

The back or uncut portion of the reflecting element, 3, may be painted a dead black or 85 otherwise darkened to prevent the reflection of light therefrom.

The photo-electric cell, 1, or glow-lamp, 1a, may be mounted in a socket, 9, upon a suitable support, 10, secured within the box, 11, in 90 any desired manner and with terminals, 10', to which the wiring system may be connected.

The lens, 2, is secured in a suitable mounting, 2', secured to the partition, 12, by set screws, 2'', or other suitable means.

In the operation of my device the object, 15, properly illuminated, is placed in front of the lens, 7, and an image of the object focused upon the screen, 6.

The rays of light from the screen, 6, are 100 then transmitted through the lenses, 5 and 4, to the scanning element, 3. The scanning element is mounted with its axis parallel to the vertical axis of the screen, 6. The length of the scanning portion of the scanning element, 3, is sufficient to cover all the parallel rays of light transmitted from the screen, 6. The rays of light reaching the first or upper mirror upon the scanning element, are reflected to the photo-electric cell, 1, but as they 105 must pass through the slot, 8a; in order to reach the cell, 1, they reach the cell in narrow pencils of light rather than in a broad band, which pencils, however, are continuous and not separated by intervening dark spots. As 110 the mirror revolves with the shaft, it catches the light rays preferably from one side of the screen first, and follows this by catching the successive rays coming from a band across the screen and transmitting them to the 115 photo-electric cell.

In case no screen is used, a combination of lenses will be necessary which will reduce the area of the parallel rays coming to the scanning element to equal the length of the body thereof or if desired, a large scanning element can be used equal in length to the length of the object to be transmitted and as the various mirrors revolve in parallel planes, they 125 will successively and respectively transmit to 130

the cell, 1, only the portion of the object which lies in the various planes. Of course this would require a correspondingly large photo-electric cell, but large cells have been

5 made large enough to receive many subjects in this way, or if desired, the mirrors of the scanning element may be inclined sufficiently, longitudinally of the shaft, to condense the rays somewhat at the photo-electric cell.

10 As no two mirrors would at any time be in a position to transmit rays from the object, 15, to the photo-electric cell, 1, at the same time, no interference could be caused by this arrangement.

15 My apparatus is primarily designed for the system of television utilizing successive transmission of circumscribed areas of a fully illuminated object, but it is equally adapted for use in those systems which illu-

20 minate the subject by illuminating successive circumscribed areas progressively and when so utilized, an arc-lamp or other intense source of light would be substituted in place of the cell, 1, in Figure 8, the lenses, 4, 5 and 25 7, and the screen, 6, eliminated and pencils of light will be reflected by the scanning element, 3, across the face of the subject in successive bands at a speed sufficient to cover the entire subject fifteen times per second 30 or thereabouts.

It is obvious that the mirrors, 3' in my scanning element may be arranged in a single spiral as shown in Figure 4 or they can be arranged in a plurality of spirals to avoid the 35 effort of the eye to follow the light beams upon the screen, it being necessary only to arrange the mirrors so that no two of them will be transmitting light rays to the same photo-electric cell at the same time. Of course a plurality of spirals may be arranged 40 with a corresponding plurality of photo-electric cells if desired, and I do not limit my claims to the precise arrangement of mirrors illustrated in the drawings.

45 My apparatus may be so arranged as to sweep or scan either the viewing screen or the image upon the focusing screen or the object itself either vertically or horizontally, but I prefer to arrange it in such a way that the scanning will begin with the upper lefthand corner and extend in successive horizontal bands across and down to the lower right-hand corner.

The number of mirrors may be varied to 50 suit the requirements of any particular case. With an angular variation of two and one-half degrees, one hundred and forty-four mirrors might be formed in a single complete spiral, thus making possible the use of a large 55 number of mirrors and correspondingly increasing the definition of the reproduction upon the viewing screen. The unit areas to be thus scanned would be comparatively small and the sharpness of definition would 60 thereby be increased. I do not limit my

claims to any precise angular variation of the mirrors nor to any precise relative number of them as both of these elements may be varied to suit varying requirements as they arise.

70

I claim:

1. In a television set, a scanning element comprising a revolvable shaft, and a plurality of narrow mirrors formed integral therewith extending transversely of the shaft parallel to and in line with the axis of the shaft.

2. In a television set, a scanning element comprising a revolvable shaft, and a plurality of narrow mirrors united thereto extending transversely of the shaft and having the successive mirrors arranged about the shaft in progressively increasing angular relation to the first mirror, the axis of the shaft passing through the surface of each mirror.

3. In a television set, a scanning element comprising a revolvable shaft, and a plurality of narrow plane mirrors united thereto extending transversely of the shaft, said mirrors having their short diameters parallel to and in line with the axis of the shaft and their long diameters at right angles thereto.

4. In a television set, a scanning element comprising a revolvable spiral shaft, and a plurality of progressively arranged narrow mirrors united thereto extending transversely of the shaft and having the axis of the shaft passing through the surface of each mirror.

5. In a television set, a scanning element comprising a revolvable shaft having one-half of the body thereof cut away on the axial line thereof to form a broad stepped-spiral face, and a plurality of narrow mirrors formed integral therewith extending transversely of the shaft upon the face of the spiral.

In testimony whereof he affixes his signature.

PAUL R. EGGER.
